UNITED STATES PATENT OFFICE.

MILO SHUTT, OF ALLIANCE, OHIO, ASSIGNOR TO THE ALLIANCE MACHINE COMPANY, OF ALLIANCE, OHIO, A CORPORATION OF OHIO.

COMBINED SOAKING-PIT, TWISTING AND STRIPPER CRANE.

Application filed February 17, 1920. Serial No. 359,249.

To all whom it may concern:

Be it known that I, MILO SHUTT, a citizen of the United States, residing at Alliance, in the county of Stark and State of Ohio, have invented a new and useful Improvement in Combined Soaking-Pit, Twisting and Stripper Cranes, of which the following is a full, clear, and exact description.

The present invention relates broadly to crane mechanism, and more particularly to a crane of the type usually referred to as a soaking pit or vertical charging crane.

The principal object of the present invention is to provide in a unitary construction a crane adapted to perform the functions of the usual soaking pit crane, and at the same time serve as a twisting and stripper crane.

Another object of the present invention is to provide a soaking pit crane which may be utilized during part of the time as a twisting crane for breaking the bottom runner from an ingot produced in a bottom pour mold, and then without change utilized for carrying the ingot and mold to any desired point, and stripping the mold therefrom.

Still another object of the present invention is to provide a traveling crane comprising a supporting trolley or carriage for all of the hoisting, twisting and stripping mechanism, all of which mechanism may be independently or simultaneously operating without corresponding movement of any part of the trolley or carriage.

A further object of the present invention is to provide a crane of the type described, comprising a bull nose which may be operated at any position of the hoisting tongs.

A still further object of the invention is to provide tongs which are effective for hoisting either ingots or molds of varying sizes and contours.

The foregoing and other objects, together with their attendant advantages, will be apparent as the invention becomes better understood by reference to the accompanying specification and drawings forming a part thereof, it being premised that changes may be made in the various details and the manner of operation within the scope of the appended claims without departing from the spirit of the invention.

Figure 1 is a side elevation of my im-

proved crane in position on a movable crane bridge.

Figure 2 is a front elevation of the construction illustrated in Figure 1.

Figure 3 is a top plan view of the supporting trolley or carriage.

Figure 4 is an enlarged view partly broken away and partly in section on the line IV—IV of Figure 3.

Figure 5 is an enlarged side view partly broken away illustrating the hoisting, twisting and stripping mechanisms.

Figure 6 is a cross sectional view on the line VI—VI of Figure 4, the tongs being in their lower position.

Figure 7 is a diagrammatic illustration of the tongs operating cables; and

Figure 8 is a diagrammatic illustration of the hoisting cables.

At the present time it is customary to provide cranes which may be utilized for stripping ingots from their molds. After the stripping operation has been performed, separate cranes are employed for carrying the ingots to the soaking pits. By means of the present invention it is possible to perform all of the necessary operations on both the molds and the ingots with the use of a single structure. It will be apparent therefore that by means of the present invention the handling of ingots may be much more expeditiously performed.

Referring more particularly to the drawings, there is illustrated a movable crane bridge 2 having tracks 4 thereon for the wheels 5 of the supporting trolley or carriage 6 of the crane. This carriage is adapted to be moved to the desired position on the movable crane bridge by means of the usual trolley motor 7. Depending from the trolley or carriage 6 is a circular protecting casing 8 provided with internal vertically extending guide-ways 9 for the rectangular casing which is adapted to slide vertically therein.

The lower end of the rectangular casing 10 carries a bearing 11, having a central hub 12 within which is rotatably mounted a sleeve 14. Splined to the lower portion of the sleeve so as to be rotated in unison therewith, is a second sleeve 15, having formed on its lower end a cross-head 16 to the outer ends of which are pivoted, intermediate their length, the tongs 17. The lower ends of the

tongs are provided both with gripping recesses 18 and points 19, thereby adapting the same for utilization with molds and ingots of various sizes and contours. The upper 5 ends of the tongs 17 are provided with rollers 20 fitting the inclined guide-ways 21 on the guide member 22 splined to the sleeve 14. For lifting the cross-head 16 relatively to the guide member 22, for opening and closing 10 the tongs, there is provided a tubular member 24 secured to the sleeve 15 and carrying at its upper end a head 25 cooperating with the lower sheave block 26. It will be apparent that upon raising and lowering the 15 sheave block 26, the tubular member 24 will be correspondingly raised or lowered and the tongs 17 closed or opened respectively. This movement of the sheave block 26 is accomplished in the usual manner by means of 20 cables 27, which cables are attached at one end to a hoisting drum 28 and from this point each of the cables passes downwardly around one of the inner sheaves 29, and thence upwardly over the fixed idler 30 carried by the trolley 6 within the protecting 25 casing 8. From the idlers 30 each of the cables again passes downwardly around one of the other sheaves 31 in the sheave block 26 and thence upwardly over one of the 30 sheaves 32 to a counterweight 34. Each of the sheaves 32 may be of any desired construction but is preferably built in accordance with the patent to Kendall No. 1,236,089, so that the maximum lifting power which 35 may be imparted to the cables is limited. Rotation is imparted to the sheaves 32 by means of a tongs operating motor 34' connected to the sheaves through the usual gearing 35.

40 For rotating the tongs for the purpose of twisting the ingot free from the runner produced during the bottom pour operation, there is splined to the sleeve 14 a gear 36 meshing with a spur gear 37 on the lower 45 end of the square twisting shaft 38. This shaft may be suitably journaled below the gear 37 in the bearing 11. The upper end of the shaft telescopes in driving relation within a tubular shaft 39 carried by the trolley 6 in which it is journaled and provided at its 50 upper end with a gear 40 meshing with a similar gear 41 on the shaft 42. This shaft is adapted to be rotated by the twisting motor 44 having the usual reduction gear 45 driving the bevel gears 46.

55 From the foregoing it will be apparent that means are provided which may be operated independently or simultaneously for opening or closing the tongs and for rotating the tongs. It is also essential that means be provided for hoisting the tongs so that the ingot and mold may be carried to the desired point. This is accomplished by hoisting cables 47 secured at one end to the drum 28 and then each passing around one of the

inner sheaves 48 in the sheave block 49 carried by the rectangular casing 10. From the sheaves 48 the cables pass upwardly around the fixed idlers 49' corresponding to the fixed idlers 30 and thence downwardly over the 70 outer sheaves 51. From these sheaves the cables pass over idle pulleys 52 to the counterweight 54. The drum 28 is provided on its opposite ends with right and left grooves 55 in which the hoisting cables are adapted to lie and corresponding grooves 56 in which the tongs operating cables 27 are adapted to lie. The drum 28 is adapted to be driven in the usual manner by the hoisting motor 59 through suitable gearing. Upon actuation of the motor 59 the drum 28 will be rotated to simultaneously wrap therearound both the cables 27 and the cables 47, so that the rectangular casing 10 and all of the mechanism carried thereby will be simultaneously raised 85 within the protecting casing 8 in the guide-ways 9.

The present construction is adapted, however, to perform an additional operation usually referred to as stripping. This is performed by providing a bull nose 60 located within the tubular member 24, and having its upper end threaded through the nut 61 carried by the sleeve 62 suitably journaled within the intermediate sheave block 49. The 90 sleeve 62 has splined thereto a stripping gear 64 meshing with a similar gear 65 on the square shaft 66. This shaft, in the manner of the twisting shaft 38, is slidable in driving relation within the tubular shaft 67, carried 100 by the trolley 6 and adapted to be rotated by the stripping motor 68 through the reduction gearing 69, the bevel gears 70 and the spur gears 71, as will be readily understood. When the stripping motor 68 is operated, the 105 shaft 66 will be rotated which will in turn impart rotation to the nut 61 causing the bull nose 60 to travel upwardly or downwardly. If forced downwardly while the mold is supported to the tongs 17, it will be apparent 110 that the ingot will be pushed downwardly out of the mold.

The advantages of the present invention arise from a construction with which it is possible to perform all of the functions of a 115 soaking pit crane, a twisting crane and a stripper crane. Further advantages arise from the provision of means whereby the operations may be independently or simultaneously carried out.

120 Still further advantages arise from the provision of a rigidly supported traveling carriage on which are located the various operating motors, which motors are capable of producing the required movements without a corresponding movement of any part of the carriage itself.

I claim:

1. A crane comprising hoisting means, twisting means, stripping means operable 130

independently of said twisting means, and mechanism for operating any of said means at will, substantially as described.

2. A crane comprising tongs, means for rotating said tongs, means for hoisting said tongs, a stripper cooperating therewith, and means independent of said first mentioned means for operating said stripper, substantially as described.

10 3. A crane comprising tongs, means for rotating said tongs, means for hoisting said tongs, a bull nose cooperating therewith, and means independent of said first mentioned means for operating said bull nose to strip 15 an ingot from the mold while supported by said tongs, substantially as described.

4. A crane comprising a support, guides carried by said support, a casing slidable in said guides, tongs mounted for bodily movement relative to said casing, means for causing relative bodily movement between said casing and tongs, means cooperating with said tongs for positively opening and closing the same upon relative bodily movement 25 between said tongs and casing, and means for simultaneously hoisting said casing and tongs, substantially as described.

5. A crane comprising a support, guides carried by said support, a casing slidable in said guides, tongs mounted for bodily movement relative to said casing, means for causing relative bodily movement between said casing and tongs, means cooperating with said tongs for opening and closing the same 35 upon relative bodily movement between said tongs and casing, means for simultaneously hoisting said casing and tongs, a stripper movable independently of said casing, and means for operating said stripper, substantially 40 as described.

6. A crane comprising a support, guides carried thereby, a casing slidable in said guides, tongs carried by said casing, means for simultaneously hoisting said casing and said tongs, means for opening and closing said tongs, means for rotating said tongs, stripping mechanism co-operating with said tongs, and means independent of said last mentioned means for operating said stripping 45 means, substantially as described.

7. A crane comprising a support, a protecting casing depending therefrom, guides in said casing, a second casing slidable in said guides, tongs carried by said last men-

tioned casing, means for simultaneously 55 hoisting said last mentioned casing and said tongs, means for opening and closing said tongs, means for rotating said tongs, stripping mechanism co-operating with said tongs, and means independent of said last 60 mentioned means for operating said stripping means, substantially as described.

8. A crane comprising a support, guides carried thereby, a casing slidable in said guides, tongs carried by said casing, means 65 for simultaneously hoisting said casing and said tongs, means for opening and closing said tongs, means for rotating said tongs, a bull nose co-operating with said tongs, and means independent of said last-mentioned means for operating said bull nose, 70 substantially as described.

9. A crane comprising a support, a protecting casing depending therefrom, guides in said casing, a second casing slidable in 75 said guides, tongs carried by said last mentioned casing, means for simultaneously hoisting said last mentioned casing and said tongs, means for opening and closing said tongs, means for rotating said tongs, a stripping mechanism movable with said last mentioned casing, and means for operating said stripping mechanism independently of the casing, substantially as described.

10. A crane comprising a support, tongs 85 carried thereby, means for raising and lowering said tongs, means for opening and closing said tongs, means for rotating said tongs, said last mentioned means comprising a motor on said support having an extensible driving connection with said tongs, stripping mechanism co-operating with said tongs, and means for operating said mechanism in any position of said tongs and independently of the means for rotating said 90 tongs, substantially as described.

11. A crane comprising a support, a casing carried thereby, tongs carried by said casing, means for rotating said tongs independently of said casing, means for hoisting 100 said tongs, and a reciprocating stripping mechanism carried by said casing and co-operating with said tongs, substantially as described.

In testimony whereof, I have hereunto set 105 my hand.

MILO SHUTT.
